METHOD OF MAKING HOSIERY

Joseph L. Beers, Bloomfield, N. J., and Hans J. Straussberger, Brooklyn, N. Y., assignors to Julius Kayser & Co., Brooklyn, N. Y.

Original application January 6, 1938, Serial No. 183,572. Divided and this application May 19, 1938, Serial No. 208,796

9 Claims. (Cl. 66—183)

The present invention relates to a method of making hosiery, more particularly to a method of manufacturing stockings of the type commonly known in the art as mesh stockings and having a 5 combined leg and instep portion cut to shape from open work fabric, such as mesh, lace, or like material, and welt and foot sections of weft knitted fabric. Specifically, the invention pertains to the method disclosed in our co-pending 10 application, Serial Number 183,572, filed January 6, 1938, of which this application is a division.

The invention has for one of its main objects the provision of a method of making the welt section and the foot section and of uniting the 15 same to the corresponding parts of the combined leg and instep portion, whereby to provide an improved connection therebetween.

Another important object of the invention resides in the provision of an improved method of 20 knitting a full-fashioned fabric foot blank intended to be connected to a cut open work fabric leg blank in such a manner that there is produced between the fabrics a reinforced and finished connection capable of resisting strain 25 and stresses to which the stocking is subjected when put to ordinary use, while adapted to impart a smooth finished appearance at the points of the fabric interconnection.

It is still another important object of the 30 invention to provide a method of knitting a stocking part and uniting the same to a stocking leg fabric section, whereby to produce an invisible combined interknitted and stitched or sewed connection therebetween.

The invention further contemplates the 35 provision of a method of knitting the welt and foot fabrics and connecting them to a combined leg and instep fabric in such a way that the plurality of fabric thicknesses are formed, between which 40 is inserted and imprisoned a substantial amount of the leg fabric, thereby producing a seam having an increased strength and a pleasing, finished appearance.

Other objects and advantages of the invention 45 will be in part obvious and in part pointed out hereinafter.

In order that the invention and its mode of 50 operation may be readily understood by persons skilled in the art, we have, in the accompanying drawings and in the detailed description based thereupon, set out possible embodiments of the invention.

In these drawings:

55 Figure 1 is an elevation illustrating a finished

stocking constructed in accordance with the invention.

Figure 2 is a composite view illustrating the cut leg and instep blank, and the welt and foot construction. 5

Figures 3 to 7 inclusive are diagrammatic representations of the various steps followed in knitting the foot fabric.

Figure 8 is a detail in perspective illustrating one mode of connecting the leg fabric blank with 10 a part of the foot fabric.

Figure 9 is a section taken on line 9—9 of Figure 8.

Figures 10 to 15 inclusive are diagrammatic representations of the steps followed in knitting 15 the welt and uniting it to the leg blank.

Having more particular reference to the drawings, wherein like characters of reference will designate corresponding parts throughout, we have shown in Figure 1 a complete and finished 20 stocking 1 consisting of a leg 2, including an instep 3, a foot 4, and a welt 5.

The leg 2 is preferably formed with a leg fabric blank 6 cut, substantially in the shape represented in Figure 2, from a sheet of suitable fabric, 25 preferably mesh, lace, or open work warp knit fabric. It will be noted that the opposite side edges 7 of the blank 6 from the marginal edge 8 along the line a—a at one end of said blank are cut and fashioned so that the blank will suitably fit the shape of a human leg when said edges 7 are sewed together to form the stocking. 30

It will also be noted that the edges 9 along the line b—b at the lower portion of the blank 6, are cut at substantially right angles with respect 35 to the edges 7 and to the edges 10, the latter extending between the points defined by said line b—b and line c—c which is along the marginal edge 11 at the other end of the blank.

Attention is called to the fact that the opposite 40 portions of the leg fabric blank adjacent the marginal edges 9 and 10 are longitudinally slit, as shown at 12, whereby to provide a pair of depending tabs 13 for the purpose to be later specified. 45

It is, of course, to be understood that the cutting of the blank along the edges 9, as shown herein, is specifically intended for the formation of an ordinary high-splice heel, but if it is desirable to form a different type of heel, such 50 as a pointed heel, then the blank may be cut so that the edges 9 will be at an angle different from that shown, in order to adapt itself to the formation of the desired type of heel.

The section of the blank from the line b—b 55

to the line *c-c* (the length of which section may vary, depending upon the foot size), constitutes the instep 3, and those portions thereof adjacent the edges 9, 10, and 11 are adapted to be connected to our improved foot 4, the construction of which is more clearly shown in Figure 2.

As represented in said Figure 2, the foot 4 is made from a full-fashioned fabric blank 14 comprising a pair of complementary heel fabrics 15, 10 a pair of complementary sole fabrics 16, and a toe fabric 17.

One end of each heel fabric 15 is provided with a double-ply welt-like fabric projection 18 extending from the heel fabric demarking line 19. 15 The other end of each heel fabric 15 is provided with a topping course 20 and a topping tab 22. It will, of course, be understood that each heel fabric may be narrowed, as shown at 23, to impart a proper curve shaping to one selvedge 20 edge 24 thereof, the other selvedge edge 25 being substantially straight. In this connection, it is to be noted that the selvedge edges 26 and 27 of the welt-like fabric projection 18 extend as a continuation of the selvedge edges 24 and 25 of the heel fabrics. Whereas the two heel fabrics 25 15 are of identical construction, they are so manufactured that one serves as the right heel and the other as the left heel.

The sole fabrics 16 start at the selvedge edges 30 25 of the heel fabrics 15, extend therefrom for a length sufficient to correspond to the desired size of the foot being knitted and terminate at the point where the knitting of the toe begins.

Each sole fabric 16 may be narrowed in the 35 usual way in the vicinity of its starting and terminating portions, as represented at 28 and 29, whereby the outer selvedge edges 30 may assume the proper curve shape, the inner selvedge edge 31 remaining substantially straight.

40 The toe fabric 17 has its side portions 32 interknit with the sole fabrics 16 so that the selvedge edges 33 of said toe fabric become a continuation of the outer selvedge edges 30 of the sole fabrics.

Interknit, as at 34, to the intermediate portion 45 of the toe fabric, is a double-ply welt-like portion 35 extending between the sole fabrics 16 and having a width slightly greater than the distance from the inner selvedge of one of said sole fabrics to the inner selvedge of the remaining sole fabric so that the selvedge edges 36 of said welt-like portion 35 overlap the selvedge edges 31 of said sole fabrics.

The usual gores 38, topping course 39, and topping tab 40, may be provided in the toe fabric 17.

55 The welt 5 may be of any suitable or desirable construction but, as represented in the drawings, is preferably made from a flat knitted fabric blank 41 of general rectangular formation with the selvedge edges 42 thereof adapted to become 60 substantially aligned with the selvedge edges of the adjacent portion of the leg fabric blank 6 when connected thereto. The welt fabric blank 41 also is preferably provided with a medial picot course 43 along which said blank is folded, whereby to form the commonly known double welt.

In knitting the foot blank, the heel fabrics 15 are first made on any type of flat knitting machine capable of adapting itself to the work, for instance, on the well known "Reading" full-fashioned knitting machine with which those skilled in the art are familiar.

The mode of procedure in knitting the heel fabrics will be clearly understood by the showing made in Figures 3 to 7 inclusive.

75 When starting the heel fabrics, an ordinary

welt bar W is brought into operative relation with the needles N, sinkers S, and knockover bits K to engage, in the usual way, the initial knitted courses and subsequently draw the fabric out of the knitting field as the knitting of said fabric progresses.

A sufficient number of courses are knitted to form the welt-like fabric projection 18 which is folded over, welt fashion, as indicated by the arrow A in Figure 3, to provide a double thickness of fabric. It will be noted that during the knitting of said projection, the fabric is slightly narrowed, then widened, as shown at 44 and 45 respectively, and a pair of picot courses 46 are knitted in spaced relation so that, upon folding the fabric to form the double thickness, the narrowed and widened portions 44 and 45 and the picot courses 46 will lay in diametrically opposed relationship.

With completion of the welt-like fabric projection 18, the knitting is continued, as shown in Figure 4, to finish the heel fabric 15 which is narrowed, as at 23, to impart shaping thereto and terminates with the ordinary topping course 20 and topping tab 22. As hereinbefore stated, 25 the heel fabrics 15 are so knitted that one forms the right heel while the other forms the left heel.

It will be appreciated that the heel fabrics of the character described may be manufactured in stock quantities and at odd times, inasmuch as 30 the heel fabrics need not be utilized immediately but may be stored for future use when foot blanks are required.

When making the foot blank 14, two completed heel fabrics 15, that is, one right and one left 35 heel fabric, are transferred on a knitting section of a commonly known full-fashioned footer knitting machine by engaging the loops at the selvedge edge 25 of said heel fabrics with a certain number of end needles, the heel fabrics 40 being relatively disposed so that the welt-like projections 18 will be facing each other in a manner more fully represented in Figure 5. The two heel fabrics 15 are so placed on the needles of the footer knitting machine that the distance therebetween will correspond to the width of the 45 instep.

With the heel fabrics thus transferred on the knitting machine, the latter is operated to simultaneously knit the pair of sole fabrics 16, one sole 50 fabric being knitted onto each heel fabric. In knitting the sole fabrics, we prefer to use one yarn carrier to form each sole fabric, each carrier being separately operated, that is, each carrier being individually connected to a separate carrier 55 bar operable through the usual well-known yarn feeding mechanism of an ordinary full-fashioned footer to impart an independent reciprocatory movement to the respective carriers for causing the same to lay their yarn over the required number of needles.

Of course, it is to be understood that additional carriers may be brought in, to work in conjunction with each of the main carriers, for instance, when it is desirable to lay a reinforcing thread or 65 to knit a plated fabric and, in that event, the additional carriers are adjusted to operate in proper relation with respect to the main carriers, a matter well understood by those skilled in the art.

During the knitting of the sole fabrics 16, the usual narrowing mechanism is caused to function, as is well known in the art, to form the narrowings 28 and 29 for the purpose hereinbefore specified.

When there has been knitted a sufficient amount of courses to constitute the sole fabrics, that is, when the knitting has been carried out to the point where the knitting of the toe is to begin, the machine is stopped and a small ready-made welt portion 35 is topped on the intermediate needles N1 so as to span the spacing between the sole fabrics. In order to facilitate the topping operation, the small welt portion is preferably provided with a topping course 48 and topping tab 49 which may be raveled out after serving its purpose. The small welt portion 35 is moreover provided with intermediate picot courses 46' similar to those provided in the welt-like projections of the heel fabrics 15. The various fabrics being thus arranged, the knitting is carried out so that the yarn is fed in one continuous stroke over the end and intermediate needles to knit the toe fabric 17 which thus becomes interknitted with said sole fabrics 16 and small welt portion 35, as indicated at 34.

In knitting the toe fabric, the narrowing mechanism of the knitting machine is operated to form the toe gores 38; the knitting machine is further operated to knit the topping course 39 and topping tab 40 onto the toe fabric 17.

Attention is called to the fact that the narrowing marks 29 at the terminating portion of the sole fabrics 16 are preferably located to converge towards the connecting point between said sole fabrics and the small welt portion 35. In this manner, there is formed a simulated diamond point resembling the diamond point in the toe, which imparts a pleasing symmetrical appearance as illustrated in Figures 1, 2, and 7.

The completed foot blank is then ready to be connected to the leg blank and the steps which we prefer to follow in effecting this connection will now be described.

40 The welt-like projections 18 of the heel fabrics 15 and the small welt portion 35 of the toe fabric 17 are folded along their respective picot courses 46 and 46' in the manner more clearly shown in Figures 8 and 9, thus forming a re-entrant portion 50 between the walls of which is inserted the corresponding portions of the leg fabric blank, that is, the depending tabs 13 and the lower marginal portion of the instep adjacent the edge 11.

50 The layers of fabrics are then sewed through and through, preferably by means of a triple needle stitching machine, thus forming a rigid seam between the leg and foot at the heel and toe parts, said seams consisting of three lines of 55 stitchings, as represented at 51. Because of the provision of the picot courses 46 and 46', it will be appreciated that finished edges 52 appear at the seam which, in connection with the lines of stitchings 51, enhance the general appearance of the stocking.

60 Moreover, the provision of the picot courses facilitates the folding of the welt-like fabric projection and the small welt portion because the picot courses tend to crimp the fabric along a straight line.

65 The seaming of the heel and toe fabrics, of course, leaves free the marginal side edges 10 of the instep 3, which edges may then be sewed or seamed, according to the usual mode of procedure, to the corresponding selvedge edges 27 of the heel welt-like projections 18 and to the selvedge edges 31 of the sole fabrics to form the seam 53 (Figure 1), said seam 53 continuing along the selvedge edges 36 of the toe welt-like portion 35, thereby joining the latter to the sole fabrics and

thus completing the connection of the foot blank to the leg blank.

Although the welt blank 41 may be connected to the corresponding portion of the leg blank in any suitable manner, we prefer to effect the connection as follows:

5 The welt blank 41 is knitted upon any suitable well known knitting machine. Prior to the turning of the welt, the corresponding portion of the leg fabric blank 6 adjacent the edge 8 thereof 10 is topped on the knitting needles N2 so that a short section 6a of said leg fabric blank projects from the inner side of the needles, the remaining portion of the leg fabric blank being allowed to drop off one side of the welt blank, as represented 15 in Figure 10 of the drawings.

The welt blank is then turned, as is customary, and a course of knitted loops 41a is formed to interknit the walls of the welt blank with the corresponding portions of the leg fabric blank 20 therebetween; the short section 6a of the leg fabric blank is subsequently brought over the needles to disengage the same and a few courses knitted to provide a welt extension 41b substantially equal in size to the short section 6a of the leg fabric blank. The welt blank is then removed off the machine and, as shown in Figure 14, the welt extension 41b and short section 6a of leg fabric blank sewed together, preferably by means of a triple needle stitching machine, as 25 illustrated at 54'. The welt blank is finally turned inside out, as shown in Figure 15, forming a hem 55' enclosing the interknit and seamed connection, after which the stocking is completed, as hereinbefore described.

30 It is also to be understood that the welt may be attached to the leg in the same manner as done at the heel and toe, by forming the welt with the necessary extension.

35 In concluding, we wish it to be understood that other modifications in the mode of practicing and constructing the invention may be made and, therefore, any modifications coming within the scope of the subjoined claims are to be considered within the spirit of the invention.

40 What we claim is:

1. The method of knitting a full-fashioned foot fabric blank comprising knitting heel fabrics with a double ply welt-like extension projecting therefrom, transferring said heel fabrics to knit thereonto sole fabrics extending in a direction at substantially right angles to that of said welt-like extension, and knitting a toe fabric as a continuation of the sole fabrics with a double 50 ply welt extension projecting between the sole 55 fabrics.

2. The method of knitting a full-fashioned foot fabric blank adapted to be connected to a cut open-work fabric leg blank comprising knitting heel fabrics with a double ply welt-like extension projecting therefrom for connection to the corresponding portion of the leg fabric, transferring said heel fabrics to knit thereonto sole fabrics extending in a direction at substantially right angles to that of said welt extension and knitting a toe fabric as a continuation of said sole fabrics with a double ply welt extension projecting between the sole fabrics for interconnection to the corresponding portion of the leg fabric.

3. The method of uniting a stocking leg fabric section with the fabric of another part of a stocking having a double ply welt-like extension provided with a reentrant portion, comprising: engaging the corresponding portion of said leg fabric 70

75

section within the reentrant portion, and securing the engaged fabric portions together.

5 4. The method of uniting a stocking leg fabric section with the fabric of another part of a stocking having a double ply welt-like extension provided with a reentrant portion, comprising: engaging the corresponding portion of said leg fabric section within the reentrant portion, and stitching the latter with said leg fabric portion.

10 5. The method of uniting a stocking leg fabric section having depending tabs with the fabric of another part of a stocking having a double ply welt-like extension provided with a reentrant portion, comprising: engaging said depending tabs within said reentrant portion, and securing together the engaged tabs and reentrant portion.

15 6. The method of uniting a stocking leg fabric section having depending tabs with the fabric of another part of a stocking having a double ply 20 welt-like extension provided with a reentrant portion, comprising: engaging said depending tabs within said reentrant portion, and stitching the latter with said tabs therebetween.

25 7. The method of making a stocking of the character described comprising: knitting heel fabrics with a double ply welt-like extension projecting therefrom; transferring said heel fabrics to knit thereonto sole fabrics extending in a direction at substantially right angles to that of 30 said welt-like extension; knitting a toe fabric as a continuation of the sole fabrics with a double ply welt extension projecting between the sole fabrics; cutting a combination leg and instep blank out of open work mesh-like material; folding 35 said double ply welt-like extensions to form a reentrant portion; and securing the corre-

sponding portions of said blank to said extensions within the reentrant portions thereof.

8. The method of making a stocking of the character described comprising: knitting heel fabrics with a double ply welt-like extension projecting therefrom; transferring said heel fabrics to knit thereonto sole fabrics extending in a direction at substantially right angles to that of 10 said welt-like extension; knitting a toe fabric as a continuation of the sole fabrics with a double 15 ply welt extension projecting between the sole fabrics; cutting a combination leg and instep blank out of open work mesh-like material; folding 20 said double ply welt-like extensions to form a reentrant portion; inserting into said reentrant portion the corresponding portion of said blank; and stitching said folded welt-like extensions with the portion of the blank therebetween.

9. The method of making a stocking of the character described comprising: knitting heel 25 fabrics with a double ply welt-like extension projecting therefrom; forming a picot course in each ply; transferring said heel fabrics to knit thereonto sole fabrics extending in a direction at substantially right angles to that of 30 said welt-like extensions; knitting a toe fabric as a continuation of the sole fabrics with a double 35 ply welt extension projecting between said sole fabrics; forming a picot course in each ply of said latter extension; folding said double ply welt-like extensions along the picot courses thereof to form a reentrant portion with outer picot edges; and securing the corresponding portions of said blank to said extensions within the reentrant portions thereof.
